UNITED STATES PATENT OFFICE.

MELCHIOR ZWICKY, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

SAFETY BRAKE STOP FOR KNITTING MACHINES.

Application filed May 27, 1925. Serial No. 33,141.

This invention relates particularly to so-called straight or full-fashioned knitting machines which are made up of a series of knitting sections operated from a common camming shaft; and it consists in improved means for automatically preventing harmful reverse turning movements of said shaft such as are incidental to stopping of the normal rotation while the cams are under operating strains. The invention is fully described in connection with the accompanying drawing and clearly defined in the subjoined claim.

Fig. 1 is a diagrammatic view indicating known parts of a straight knitting machine with my invention applied thereto.

Fig. 2 is a sectional elevation clearly showing my invention in connection with a portion of the drive shaft; the movable stop for the brake-ring spreading device being illustrated in projected position.

Fig. 3 is a cross-sectional view of the brake-wheel members, on the line 3—3 of Fig. 2; the spreading device being in the position assumed during normal rotation of the shaft indicated by the arrow.

Fig. 4 is a fragmentary view corresponding with Fig. 3 but showing the ring-spreading device in an extreme braking position, towards which it is sufficiently swung by any reverse turning action of the shaft.

Fig. 1 indicates an ordinary knitting machine frame A, with the usual cam shaft B and geared hand-wheel drive shaft C mounted therein; a cam B', one of the number fixed to said cam shaft, being indicated as acting upon a lever B² for desirably moving certain mechanism when the shaft is normally rotated. The reaction of said lever upon the cams actually tends to cause objectionable reverse turnings of the shaft when normal driving is stopped; and my improved mechanism for promptly stopping such reverse rotation is shown applied to the drive shaft C, with one member thereof fixed to a frame portion A' by means of a forked arm 15^a of said member, so that said shaft C may be operated intermittently with insurance against such reverse movement.

As fully shown in Figs. 2, 3, and 4, my improved mechanism comprises two brake-wheel members 10 and 15 upon the drive shaft C; the member 10 being suitably fixed to said shaft, and the member 15 previously referred to, being fixed against rotation, as

shown, by engagement of its forked arm 15^a 55 with the frame projection A'. The non-rotatable member 15 affects the rotation of the shaft C only through the automatic action of a reverse-motion stop device 16 eccentrically pivoted thereto at 17 and operative upon 60 a split brake-ring 20 interposed between the members, as hereinafter more fully described.

The split ring 20 is adapted to fit within an overhanging circular flange 10^a of the shaft-fixed member 10, with its end portions 65 spread so as to provide a split-gap 20^a between them; while the frame-fixed member 15 has a hub portion 15^b loosely projecting into said ring and provided with a recess 15^c for the pivoted ring-spreading device 16. 70 The tip portion 16^a of the latter is wedge-shaped as shown; and in the normal position of the device as shown in Fig. 3 and indicated by dotted lines in Fig. 4, it is seated against the recess wall 15^c in non-radial position, 75 with said tip portion projected into the split-gap 20^a of the ring, so as to prevent rotation of the latter with the freely rotatable shaft-fixed member 10. The device 16 is movable from this normal position only in case a reverse turning action is exerted upon the shaft 80 C and its fixed member 10.

As already mentioned, such reverse-turning action occurs when the normal rotation of the machine is stopped with cams B' acting to operate levers B²; and the object is to promptly neutralize such action by making the split ring 20 serve as a brake; this being accomplished by the wedge action of the tip 16^a engaged in the split-gap 20^a. This action is 85 clearly brought out in Fig. 4, where the normal projection of the wedge-tip into the split-gap is indicated in dotted lines, while its greater projection to spread the ring for braking is shown in full lines. This greater 90 projection into the split-gap is caused by the swinging of the spreader device 16 on its pivot 17 as soon as any reverse-turning action begins; the fit of the ring 20 in the overhanging flange 10^a of member 10 making it partake of 95 any reverse-turning tendency sufficiently to cause this swinging of the device 16 towards a position radial to the shaft, with resulting 100 spread of the ring and gripping action upon the member 10 to brake the latter. It will be 105 understood that this braking action is readily made effective with less swing of the pivoted device 16 than is illustratively shown; and

that the resumption of normal rotative action just as promptly releases the brake.

In order that reverse turning movement of the machine may be made possible, it is necessary that the ring-spreading device 16 be made inoperative as a braking means when desired; and for readily accomplishing this I provide a plunger stop 25 movable by hand in a slide-way 26 formed in the non-rotative member 15 so as to either project into the swinging path of said device 16 as shown in Fig. 2, or to be withdrawn therefrom for securing automatic brake action as described.

What I claim is:

15 In combination with a frame-mounted shaft, of a reverse-turning braking device for said shaft comprising cooperating brake-wheel members thereon, one of which is fixed to rotate therewith and the other having a non-rotative engagement with the frame, and a

flange portion of one of said members encircling an extending hub portion of the other member, a split brake-ring interposed between said flange and hub portions, a walled recess in the latter, a limitedly movable brake-ring-spreading device pivotally mounted in said recess and having a wedge-shaped end projected between the ends of said split ring; said spreading device being moved into idle non-ring-spreading position against one wall of 30 said recess by turning movement of the shaft in one direction, and being moved to the opposite recess wall by reverse shaft turning movement to further project its wedge shaped end in a ring-spreading action, and a lock pin 35 movable to retain said spreading device in idle wall contact.

In testimony whereof, I hereto affix my signature.

MELCHIOR ZWICKY.
